INVENTOR:
John H. Grady,
BY Dwight Wagner,
ATTORNEY.

UNITED STATES PATENT OFFICE

2,006,861

BALL

John H. Grady, St. Louis, Mo., assignor to J. H. Grady Manufacturing Company, St. Louis, Mo., a corporation of Missouri

Application July 21, 1932, Serial No. 623,709

1 Claim. (Cl. 112—262)

This invention relates to playing balls, and more particularly to balls having a relatively solid core and a hide cover thereon, such as base balls, playground balls, and the like.

5 The principal purpose of the invention is to provide a covered ball whose seams will be sewn together by a novel form of stitching that will be stronger, and much more durable and resistant to wear than the conventional V-shaped ball stitch hitherto employed, but which will not require more cover material, extra lining for the cover material, much more thread, or much more labor and expense than would be necessary in the manufacture of the conventional V-stitch ball.

10 Another object is to provide a style of cover stitching whose tactile characteristics are such as will enable the player to hold the ball much more firmly than hitherto, but without producing a sense of undue roughness.

15 Other objects, advantages, and desirable features of the invention will appear in the course of the following description of an illustrative embodiment of the spirit thereof.

20 In the accompanying drawing forming part of this specification, in which like numbers of reference denote like parts wherever they occur,

25 Figure 1 is a perspective view of a ball made in accordance with this invention;

30 Figure 2 is a fragmentary enlargement view particularly showing the novel form of stitching;

35 Figure 3 is a fragmentary view of the inside of the partly stitched cover;

40 Figure 4 is a fragmentary section, taken on the line 4—4 in Figure 2;

45 Figure 5 is a fragmentary section, taken on the line 5—5 in Figure 2; and

50 Figure 6 is a fragmentary section, taken on the line 6—6 in Figure 2.

The invention may be embodied in a ball having the usual wound-thread core 1 and the conventional cover sections 2 and 3, provided along their edges with the usual pre-formed perforations 4. The two threads 5 and 6 may be of any desired style, the two-strand five-ply type being used in the present instance. The ends of the threads are suitably secured preparatory to stitching, as exemplified by their anchoring loops

55 7 taken through the core 1. The cover sections 2 and 3 are then placed in position on the core, and the thread 5 is passed through an adjacent perforation 4 to the outside of the cover, and thence diagonally toward the right and forwardly across the edges 8 of the cover as at 9,

through the next perforation 4 on that side of the edges 8 to the inside of the cover, and thence straight across, underneath, as at 10, to the perforation 4 directly opposite the last-mentioned perforation 4, and thence therethrough to the outside of the cover. The thread 6 is then passed through the perforation 4, located directly opposite the aforesaid first-mentioned perforation, and thence, as at 11, diagonally to the left and forwardly across the first lap 9 of the 10 thread 5, thence through the aforesaid third-mentioned perforation to the underside of the cover, and thence coextensive, as at 12, with the last lap 10 of the thread 5 and into and through the perforation directly opposite. The 15 aforesaid cycle of operations is then continually repeated until the double course of stitching has been completed. It may then be continued to overlap a few of the initial stitches, as shown at 13, Figure 1, and then the threads may be 20 severed at the end of the last stitch, the overlapping being sufficient to hold the ends securely.

25 It will be observed that the double courses of stitching 5 and 6 form a series of straight lines at right angles to the seam 8 on the underside or inside of the cover, and the outline of a series of contiguous rhombic or diamond shaped figures 14 on the outside of the cover. The thickness of the threads on the inside of the cover produces an elevation of the figures 14, maintaining them in relief against their outlining threads, and so shields the threads to that extent against abrasion. Furthermore, should one of the threads on the outside have one of its 30 stitches cut or beaten through, the adjacent 35 stitches of this thread will not become loose, because they are frictionally held secure by the stitches of the other thread. Furthermore, even were the first thread to become loosened and unravelled, the second thread would still be 40 intact to hold the edges 8 together. The thread 6, being on top of the thread 5, also serves to shield the latter. The diamond-shaped elevations and their outlining threads, also, form an ideal configuration on the surface of the ball to 45 facilitate its being securely held by the player.

Having this fully described this invention, I hereby reserve the benefit of all changes in form, arrangement, order, or use of parts, as it is evident that many minor changes may be made 50 therein without departing from the spirit of this invention or the scope of the following claim.

I claim:

In a baseball, a core, a pair of cover sections having opposing edges in abutting relation, a 55

pair of courses of stitching having their free ends formed into V-shaped configurations and embedded in the said core, the said pair of courses of stitching respectively extending from one section to the other on the outside of the cover to form rhombic stitch patterns and fur-

ther respectively extending from one section to the other in abutting parallel relation across said edges at right angles thereto on the inside of the cover to elevate the portions of the cover confined within the said patterns.

JOHN H. GRADY.
